UNITED STATES PATENT OFFICE.

EDWARD B. HUNT, OF LAMPASAS, TEXAS.

DAM CONSTRUCTION.

1,088,702.

Specification of Letters Patent.

Patented Mar. 3, 1914.

Application filed September 26, 1912. Serial No. 722,425.

To all whom it may concern:

Be it known that I, EDWARD B. HUNT, a citizen of the United States, residing at Lampasas, in the county of Lampasas and 5 State of Texas, have invented certain new and useful Improvements in Dam Construction, of which the following is a specification.

My invention relates to dam constructions 10 and it has for its primary object to so construct a dam that the retainer or head wall will be of a height considerably less than the depth of the water retained thereby.

Another object of my invention is the construction of a dam provided with a substructure and a retainer or head wall carried by said substructure of considerably less height than the depth of the water retained thereby.

20 A further object is the provision of a substructure rising from the bed of the river or stream and provided with a load-carrying deck which gradually rises in the direction of the flow of the water and at its farther 25 or front end is surmounted by a retainer or head wall of a height only a comparatively small fraction of the depth of the water retained thereby.

A still further object is the provision of 30 means for permitting the water retained by the retainer or head wall to flow along the natural bed of the river or stream and underneath said wall, thus enabling repairs to be made to the wall if required.

35 Still further objects are to provide the retainer or head wall with a movable wall capable of being elevated to increase the head of the water when flood waters pass away; and to otherwise improve on dams as 40 now constructed.

To these ends the invention consists in the construction and arrangement of parts to be hereinafter described and more particularly set forth in the appended claims.

45 In the drawings forming part of this specification,—Figure 1 is a longitudinal section through a dam constructed according to my invention. Fig. 2 is a transverse section taken on line $y-y$, Fig. 1. Fig. 3 is a plan view of a portion of the dam. Fig. 4 is a broken fragmentary section of the retainer or head wall taken in a vertical plane. Fig. 5 is a horizontal section taken on line $z-z$, Fig. 4.

55 Referring now to the drawings in detail,

like characters of reference refer to like parts in the several figures.

The reference character A designates the bed of a river or stream, B the dam considered as a whole, C the substructure, and 60 D the superstructure.

The substructure C comprises a transverse or abutment wall 6 embedded into and rising above the bed of the river or stream and longitudinal walls or buttresses 7 increasing in height from said transverse or abutment wall in the direction of the flow of water, or "downstream" as it may be termed, with preferably a sharp rise at an intermediate point, as at 8. These walls may 65 be constructed of any suitable material but are preferably constructed of concrete, reinforced in any approved manner, and if desired the longitudinal walls or buttresses may be made thicker progressively as shown, 70 from their low points forward to their high points.

The longitudinal walls or buttresses 7 are spaced apart to form the intervening spaces 9, and by preference, I construct side walls 80 10 along the banks of the stream which may rise to the height of the top of the superstructure. These side walls may, however, be dispensed with where the nature of the banks of the stream permits, and in many instances would be modified from the construction herein shown. When these side walls are used the lower portions thereof may be said to form part of the substructure and the upper portion part of the superstructure. 90

The intervening spaces 9 are covered with a load-supporting deck 11 which is preferably constructed of reinforced concrete and carried by the longitudinal walls or buttresses 7, and by reason of its being carried 95 in this manner it gradually rises from the transverse abutment wall 6 forwardly with an abrupt deflection or rise at a point between its front and rear ends, as at 12. This load-supporting deck forms an artificial elevated bed for the water and may rise from front to rear to any desired height.

At the "downstream" or forward end of the longitudinal walls or buttresses 7 the superstructure proper is located, which consists of a transversely-disposed retainer or head wall 13 and beams 14 spanning the spaces 9 between said longitudinal walls or buttresses and serving to support said retainer or head wall between said longitudi- 110

nal walls or buttresses. This retainer or head wall rises from the substructure with the underside thereof flush with the underside of the load-supporting deck 11 and like the walls above referred to, it is preferably constructed of reinforced concrete. Said retainer or head wall may be a straight or curved wall, as may be desired, and in the accompanying drawings it is shown as 10 measuring from top to bottom about two-sevenths the height of the entire dam construction. This proportion may of course be changed, but under the principle involved the retainer or head wall is elevated a considerable distance above the bed of the river or stream and by reason of its being only a fraction of the height of the dam it is subjected to pressure of the water in proportion to its height although assuring a head of 15 water fully as high as a wall of much greater height. By reason of the retainer or head wall being supported in an elevated position and being of a height only a fraction of the height of the entire construction, the 20 thickness of the same need not exceed its proper proportion to its height, which results in a considerable saving in material.

By constructing the longitudinal walls or buttresses so that they incline from their 25 forward to their rear ends, the load of the water supported thereby and flowing toward the retainer or head wall is in a vertical plane with the thrust of the same in the direction of the length of the said walls or 30 buttresses and this construction further permits the transverse or abutment wall and the retainer or head wall to be made of minimum height so as to relieve the structure of the pressure of the water in a direction transversely to these walls.

The transverse or abutment wall has relief openings or passages 15 formed therein in planes between the longitudinal walls or buttresses. These openings are closed with 45 gates or closures 16 of any suitable material or construction, which may be removed to permit the water to pass through said passages and flow downstream underneath the retainer or head wall. This is a very desirable 50 feature of my invention, as it permits the water to be drained from the superstructure and the load-supporting deck so that repairs may be made to the dam when necessary.

55 I also provide the dam with a movable retainer wall 17, which may be elevated in times of flood so as to maintain the water at a greater head, and for this purpose the retainer or head wall 13 is provided with an 60 upwardly opening pocket 18 which extends from end to end thereof and in said pocket the movable retainer wall is located. Said removable retainer wall has secured thereto at intervals in its length nuts 19 which are 65 arranged in pairs, one of each being a dis-

tance from the upper edge of said wall and the other near the lower edge thereof. Threaded through each pair of said nuts is a screw shaft 20, each having a worm gear 21 at the lower end which is in mesh with a worm 22 secured to a horizontal shaft 23 extending forwardly through the head wall. The forward ends of the shafts 23 have bevel gears 24 secured thereto which are in mesh with a bevel gear 25 secured to a transversely-disposed driving shaft 26 journaled in the brackets 27 extending outward from the front face of the head wall 13.

If found desirable the screw shafts 20 may be extended above the upper edge of the 80 movable retainer wall 17 in which event the upper edge of the several pairs of nuts 19 may be placed closer to the upper edge of the retainer wall than would be otherwise possible.

At intervals in the width or length of the head wall recesses 28 are formed in which are located electrically-driven motors 29, the shaft of each having a sprocket wheel 30 around which and sprocket wheels 31 on said transversely-disposed driving shaft 26 sprocket-chains 32 are passed. As clearly shown in the drawings, the recesses 28 open through the front of the head wall 13 and are therefore protected from the water. The 95 motor with the parts between it and the screw-shafts 20 constitute the manipulating mechanism for raising and lowering the movable retainer wall, but if desired, any other form of manipulating mechanism may 100 be employed without departing from the principle involved. The several motors are run at a uniform speed so that the power is transmitted to the transversely-disposed driving shaft without twisting strain being 105 imparted thereto, and it may be here stated that the screw-shafts 20 are held against lengthwise movement in any approved manner so that the rotation of the same causes movement of the movable retainer wall.

The movable retainer wall has narrow guide pieces 33 at its upper and lower edges and similar guide pieces 34 arranged vertically at intervals in its length; these guide pieces being in contact with the front and rear walls of the pocket 18 to prevent wabbling of said movable retainer wall.

In order to stay the movable retainer wall when elevated so as to prevent the water forcing the same forward, stay cables 35 are 120 provided which are secured at one of their ends to the upper edge of said wall, as at 36, and at their other ends to the rear face of the head wall, as at 37, or to any other low points.

125 For the purpose of preventing the water which may pass over the head wall from dropping onto the manipulating mechanism of the movable retainer wall, said head wall has at its upper edge a forwardly extending 130

projecting portion 38, and secured to the front of said head wall is a platform 39 which extends almost the full width of said wall so that repairs can be easily made to the manipulating mechanism or the latter be inspected when desired.

Having thus described my invention, what I claim is,—

1. A dam having a solid head wall supported a distance above the bed of a stream or river.

2. A dam comprising a substructure and a solid head wall supported by said substructure a distance above the bed of a stream or river.

3. A dam comprising a substructure having a load-supporting deck elevated above the bed of a stream or river, and a head wall supported on said substructure at the downstream end of said load-supporting deck, said load supporting deck extending upstream from the lower end of said head wall.

4. A dam comprising a substructure having longitudinally-disposed buttresses projecting from the bed of a stream or river, a load-supporting deck carried by said buttresses, and a head wall also carried by said buttresses and arranged substantially at a right angle thereto, said buttresses and deck extending up stream a distance.

5. A dam comprising spaced longitudinally-disposed buttresses projecting from the bed of a stream or river and being of gradually increased height down-stream, an abutment wall at the up-stream ends of said buttresses, a head wall carried by the downstream ends of said buttresses, and a load-supporting deck carried by said buttresses and extending from said abutment wall to said head wall.

6. A dam construction comprising longitudinally-disposed buttresses projecting upward from the bed of a stream or river and being gradually inclined from their downstream ends to their up-stream ends with an abrupt deflection between their ends, an abutment wall arranged at a right angle to said buttresses at their up-stream ends, a head wall arranged at a right angle to said buttresses at their down-stream ends, said head wall being supported in an elevated position by said buttresses, and a load-supporting deck carried by said buttresses and extending from said abutment wall to said head wall, said load-supporting deck having an abrupt deflection at a point between its ends.

7. A dam construction comprising longitudinally-disposed buttresses spaced apart and extending upward from the bed of a river, an abutment wall arranged transversely at the up-stream end of said buttresses and having openings in line with the spaces between said buttresses, a closure

for each of said openings, a head wall supported by said buttresses at their downstream ends, and a load-supporting deck supported by said buttresses and extending from said abutment wall to said head wall.

8. A dam construction comprising longitudinally-disposed buttresses spaced apart and extending upward from the bed of a stream or river, an abutment wall at the up-stream end of said buttresses, a head wall supported by said buttresses at their downstream ends and having an upwardly opening pocket extending from end to end thereof, a load-supporting deck supported by said buttresses and extending from said abutment wall to said head wall, and a retainer wall vertically movable in said pocket and adapted to be elevated therefrom to increase the head of the water retained by the dam.

9. A dam construction comprising a head wall having an upwardly opening pocket extending from end to end thereof, a retainer wall vertically movable in said pocket, means for elevating said retainer wall to increase the head of the water retained by the dam, and means for staying said retainer wall when elevated to prevent deflection thereof under pressure of said water.

10. A dam construction comprising a head wall having a vertically sliding retainer wall adapted to be elevated above the upper edge of said head wall to increase the head of the water retained by the dam.

11. A dam construction comprising a head wall having an upwardly opening pocket extending from end to end thereof, a retainer wall located within said pocket and adapted to be elevated therefrom, and stay cables secured to the upper edge of said retainer wall with one of their ends and having their other end secured to a low point in rear of said retainer wall.

12. A dam construction comprising a head wall, a retainer wall movable with respect thereto to increase the head of the water retained thereby, a driving shaft arranged lengthwise on said head wall and extending from one end thereof to the other, means for rotating said driving shaft, and operative mechanism intermediate said driving shaft and said retainer wall for elevating and lowering the latter.

13. A dam construction comprising a head wall having an upwardly opening pocket, a retainer wall in said pocket having a plurality of pairs of nuts secured thereto, a vertically disposed screw-shaft for each pair of said nuts, a worm gear secured to each of said screw-shafts, shafts extending through a portion of said head wall from the pocket therein to the outer face thereof, a worm secured to each of said last-mentioned shafts and in mesh with the worm

gear of its corresponding screw-shaft, and means for rotating the shafts having said worms thereon at a uniform speed.

14. A dam construction comprising a head wall having recesses in its outer face, electrically-operated motors situated in said recesses, a driving shaft arranged lengthwise in front of said head wall and being rotated by said motors, a retainer wall movable vertically with respect to said head wall, a plurality of shafts rotated by said driving shaft and having operative connection with said retainer wall to raise and lower the same.

15. In a dam construction a head wall having a forwardly-extending projecting portion at its upper edge and a plurality of recesses in its front wall beneath said projecting portion, motors within said recesses, and a movable retainer wall arranged within said head wall and adapted to be elevated and lowered by actuation of said motors.

16. A dam construction comprising a head wall having an upwardly opening pocket extending from end to end thereof, a retainer wall movable within said pocket, a

driving shaft arranged lengthwise at the front face of said head wall, a platform extending lengthwise of said head wall, and operative connection between said driving shaft and said retainer wall.

17. A dam comprising a substructure having longitudinally-disposed buttresses rising from the bed of a stream or river, a load supporting deck carried by said buttresses and entirely elevated to allow the water of the stream or river to pass underneath when diverted from its course over the dam, means at the up stream end of said deck to cause the water to flow onto said deck, and a head wall also carried by said buttresses at the down stream end of said deck and arranged substantially at a right angle to said buttresses.

In testimony whereof, I have affixed my ⁴⁵ signature in the presence of two subscribing witnesses.
